[57] CLAIM

The ornamental design for a hand grip attachment for a patient's bed, as shown and described.

DESCRIPTION

FIG. 1 is a perspective view of a hand grip attachment for a patient's bed, showing my new design;

FIG. 2 is a side elevational view, the opposite side being a mirror image thereof;

FIG. 3 is a front elevational view; and

FIG. 4 is a top plan view.

Elevation views of the hand hold device from the left side and rear are a mirror image of and identical to FIGS. 2 and 3, respectively.
